UNITED STATES PATENT OFFICE.

HOWARD H. SHELTON, OF AKRON, OHIO.

DIE FOR MAKING COTTERS.

1,151,410.

Specification of Letters Patent. Patented Aug. 24, 1915.

Application filed August 3, 1914. Serial No. 854,769.

To all whom it may concern:

Be it known that I, HOWARD H. SHELTON, a citizen of the United States, residing at Akron, in the county of Summit and State 5 of Ohio, have invented new and useful Improvements in Dies for Making Cotters, of which the following is a specification.

This invention relates to improvements in dies for forming rounded or conoidally-ended blanks from which cotters or spring 10 keys are made, and the object of the invention is to fashion dies to sever a continuous strip of wire into blanks for making cotters, so that during the severing of the blanks 15 from the continuous strip of wire they will be provided with tapered, rounded or conoidally-formed ends whereby when said blanks are fashioned into cotters the shank ends of the crotter will be correspondingly 20 formed to obviate the rounding or tapering of the ends by a separate operation.

With the foregoing and other objects in view, the invention consists in the novel construction, combination and arrangement of 25 parts constituting the invention to be hereinafter specifically described and illustrated in the accompanying drawings which form a part hereof wherein is shown the preferred embodiment of the invention, but it 30 is to be understood that changes, variations and modifications can be resorted to which come within the scope of the matter hereinafter claimed.

In the drawings in which similar reference 35 numerals indicate like parts in the different figures, Figure 1, is a perspective view of a die and a co-acting punching shear with a strip of wire in the die just previous to the shearing operation; Fig. 2, is a view similar 40 to Fig. 1 after the blank has been severed from the continuous wire and with the ends of the wire and blank rounded; and, Fig. 3, is a view in side elevation of a crotter manufactured from a blank such as is shown in Fig. 2.

Referring to the drawings in detail, the 45 reference numeral 1 denotes a fixed or lower die which is usually mounted in a seat in a suitable machine equipped with mechanism for vertically reciprocating a movable or 50 upper die 2 but as the mechanism for operating the movable die 2 is unimportant to this invention it is omitted. The lower die 1 is

provided with a longitudinally extending groove 3 so fashioned in cross section as to properly receive the wire from which the 55 blanks are to be formed, as in this illustration it is approximately semi-circular in form. Intersecting the groove 3 is a recess 4 preferably with approximately vertical side walls and of a proper size to freely receive the lower working end of the movable die 2. Adjacent to the side walls of the recess 4 both ends of the groove 3 are inwardly tapered or curved at 5, as shown in the drawings, thereby reducing the openings 60 at the groove ends between the groove 3 and the recess 4. In practice, the end of a continuous wire 6 is shifted longitudinally along the groove 3 so as to extend across the recess 4 after which the movable die 2 is 65 lowered, severing the projecting end of the wire 6 into a blank 7. It will be noted that the ends of the groove 3 on both sides of the recess 4 are rounded so that the severed 70 advanced end 8 of the continuous wire and the blank end are simultaneously rounded and after another section of the continuous 75 wire is advanced and severed both ends of the blanks produced are given a tapered rounded or conoidally formed contour after 80 which the blank is shaped into the form of a crotter 9 as shown in Fig. 3. Of course the tapering or curving of the shank end 10 of the crotter is for the purpose of permitting a more easy insertion of the crotter in an 85 opening in use.

I claim:

1. Mechanism for forming crotter blanks having rounded, tapered or conoidally formed ends comprising a die having a wire-receiving groove extending in one face thereof, a recess intersecting said groove, the ends of the groove adjacent to the intersecting recess being rounded, tapered contracted or conoidally fashioned, and a shearing punch 90 adapted to pass through said recess for simultaneously severing a blank from a continuous wire and simultaneously rounding or tapering the ends of the wire.

2. Mechanism for forming crotter blanks 100 having rounded, tapered or conoidally-formed ends comprising a die having a wire-receiving groove extending in one face, and further provided with a recess intersecting

said groove, the groove adjacent to the sides of the recess tapering inwardly toward the recess and united therewith by contracted openings and a shearing punch arranged to move through said recess for severing a blank from a wire and simultaneously fashioning the ends of both wire and blank to correspond with the contour of said groove.

Copies of this patent may be obtained for five cents each, by addressing the "Commissioner of Patents, Washington, D. C."

In testimony whereof I have hereunto set my hand in presence of two subscribing witnesses.

HOWARD H. SHELTON.
